(57) **CLAIM**

The ornamental design for an automobile and toy replica thereof, as shown and described.

DESCRIPTION

FIG. 1 is a front, perspective view of an automobile and toy replica thereof of our new design;

FIG. 2 is a rear perspective view thereof;

FIG. 3 is a right side elevational view thereof, the left side elevational view being a mirror image of thereof, with the exception of the outline of the door covering the gas cap, which is not present on the opposite side;

FIG. 4 is a top plan view thereof;

FIG. 5 is front view thereof; and,

FIG. 6 is a rear view thereof.
